UNITED STATES PATENT OFFICE.

MORRIS HABER, OF NEW YORK, N. Y.

DESIGN FOR A LIQUID-GUN.

49,183.

Specification for Design.

Patented June 13, 1916.

Application filed March 16, 1916. Serial No. 84,730. Term of patent 3½ years.

To all whom it may concern:

Be it known that I, MORRIS HABER, a citizen of the United States, and residing at New York city, in the county and State of New York, have invented a new, original, and ornamental Design for Liquid-Guns, of which the following is a specification,

reference being had to the accompanying drawing, forming part thereof, which shows the liquid-gun in side elevation.

I claim:

The ornamental design for a liquid gun, as shown.

MORRIS HABER.
